DICTATING MACHINE

Gordon W. Florian, Fairfield, Conn., assignor to Dictaphone Corporation, Bridgeport, Conn., a corporation of New York

Application April 8, 1958, Serial No. 50,379

Term of patent 14 years

(Cl. D26—14)

Figure 1 is a front perspective view of a dictating machine, showing my new design;

Figure 2 is a rear perspective view;

Figure 3 is a front elevational view, to an enlarged scale;

Figure 4 is a side elevational view, to an enlarged scale;

Figure 5 is a rear elevational view, to an enlarged scale; and

Figure 6 is an opposite side elevational view thereof, to an enlarged scale.

I claim:

The ornamental design for a dictating machine, substantially as shown.
